REVERTIBLE DRAFT STOVE

Elias W. Conkell, Birmingham, Ala., assignor of
one-half to Jessie L. Lambert, Birmingham,
Ala.

Application August 26, 1940, Serial No. 354,187

1 Claim. (Cl. 126—75)

This invention relates to improvement in revertible draft magazine heating stoves and consists in the unusual arrangement, combination and construction of parts hereinafter described.

The main object is to provide a stove so that the greatest efficiency may be obtained from the fuel consumed.

In the accompanying drawings Fig. 1 is a front elevation of the assembled furnace. Fig. 2 is a part top plan view. Fig. 3 is half sectional elevation on center line. Fig. 4 is a part sectional on line 4—4 in Fig. 3. Fig. 5 is half sectional elevation on center line at 90 degree angle to other center line. Fig. 6 is a part sectional on line 6—6 in Fig. 5.

Similar reference numerals refer to similar parts throughout the several views.

By referring to the drawings it will be observed there is a fire pot indicated by 1 and 2 that may be made in one or more pieces. It is supported by a main ring or rim 3 in the stove lower portion which also supports an ash pan 5. Attached by welding or other means to the rim 3 are bracket tracks 8 for balls 7 that carry movable part 40 of the fire pot with the rocker grate bars 6. These grates 6 and movable part 40 may be removed through the door 4 when necessary. Part 40 that is movable has brackets 45 to support the shaker bar operated by the crank 9. The main radiator or heat shell 10 is corrugated to afford greater heating as its inner surface is in direct contact with the fire gases. This radiator extends from the bottom 11 to a top flange 12 except for the door spaces. Above the fire pot 1 and 2 is a magazine 33 which is charged with fuel by removing the top 37 and inner cover 43. Magazine 33 has a flange 34 that fits between top 20 of outer shell 39 as shown at 35, 36 and 42 to form a joint. Louvers 38 are for air passage. The inner edges of radiator 10 end at 24 in contact with a fire wall 27. There is a main flue 17 with a damper door 16 hand operated by the handle 47. To better control the draft the stove has an oblong baffle member with sides 22 ending short of the stove front as indicated at 48 provided with holes 30 for gas circulation. The sides 22 are held together at one end by a cross rod 29 and at the other end by a face part 23. The bottom of the stove shell has opening 28 through which the said baffle assembly is passed to rest on the bottom 32 of the stove. The front 23 of the baffle has a latch 31 to keep the baffle inserted and in place. The top of the ash compartment is indicated by 25. The stove has a main door 13, double bottom doors 4 with 55

5 draft openings 44, and legs 41. The draft is automatically controlled by a thermostat indicated by 18 that operates a damper 19 over an opening 15 that has an inspection door 14. The fire shell extends from bottom 26 above lower gas chamber to the height indicated by 27 or may be extended higher but must not come in contact with the interior top 21 of fire compartment.

10 When fire is started directly draft door 16 leading to flue is opened to allow free passage of smoke and gas to said main flue 17. After the fire is well started this draft door 16 is closed. The gas, and smoke if any, then travel upward and over inner fire shell or wall 21, then down 15 between the fire wall 21 and inner surface of the radiator 10 to main bottom and along through and around baffle assembly 22 and then up to main flue 17. By this arrangement of parts the heat from the fire rises upward, then is pulled down, then up and out. In this long passage it is slow moving and causes long contact with the parts that are adjacent the air for heating.

15 It is intended to manufacture the furnace out of any material that may be best suited for the purpose.

20 While I have shown the preferred embodiment of my invention I do not wish to limit myself to the precise and exact details of structure but reserve the right to make any and all modifications and changes so long as I remain within the spirit and scope of the following claim.

25 Having described my invention I claim:

20 A revertible draft stove comprising, the combination of a fire pot having grates therein, an inner casing supporting said fire pot and forming an ash chamber therebelow, an intermediate casing surrounding the inner casing and spaced therefrom to form a down draft passage leading to a sub-chamber beneath the ash chamber, an outer casing surrounding the last mentioned casing and forming passages for air to be heated, means forming a flue leading upwardly from said sub-chamber to a vent opening in said outer casing, thermostatically controlled damper means 35 providing communication between the ash chamber and said flue, a damper in an upper portion of said intermediate casing providing direct communication between said fire pot and vent, a draft baffle in said sub-chamber, said draft baffle 40 comprising two parallel sides with vent holes in same and held together at one end by a cross member as a brace and closure, and joined at the opposite end by a cross rod.
